Primary Examiner — Kimberly Barnes(74) *Attorney, Agent, or Firm* — Nitin Kaushik(57) **CLAIM**

The ornamental design for a connection plate for a dust bag, as shown and described.

DESCRIPTION

FIG. 1 is a top perspective view of a connection plate for a dust bag, showing my new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is another top perspective view of the connection plate for a dust bag, shown in a state of use.

The broken lines in FIG. 9 depicting a dust bag represents environmental subject matter that forms no part of the claimed design.
